[57] CLAIM

The ornamental design for a hermaphroditic electrical connector terminator unit, as shown and described.

DESCRIPTION

FIG. 1 is a top plan view of one half of a hermaphroditic electrical connector terminator unit, shown separately for clarity of illustration;

FIG. 2 is a side elevational view of FIG. 1;

FIG. 3 is a bottom plan view of FIG. 1;

FIG. 4 is a side elevational view of the side opposite that shown in FIG. 2;

FIG. 5 is a left end elevational view of FIG. 1;

FIG. 6 is a right end elevational view of FIG. 1;

FIG. 7 is a side elevational view of the other half of the unit, shown separately for clarity of illustration with the opposite side being a mirror image;

FIG. 8 is a left end elevational view of FIG. 7; and,

FIG. 9 is a side elevational view of the connector halves in assembled condition.
